UNITED STATES PATENT OFFICE.

FRANCIS S. NORTH, OF CHICAGO, ILLINOIS, ASSIGNOR TO UNION SPECIAL MACHINE COMPANY, OF CHICAGO, ILLINOIS, A CORPORATION OF ILLINOIS.

LOOPER-SUPPORT.

1,110,814.

Specification of Letters Patent. Patented Sept. 15, 1914.

Application filed October 12, 1911. Serial No. 654,328.

To all whom it may concern:

Be it known that I, FRANCIS S. NORTH, a citizen of the United States, residing at Chicago, in the county of Cook, State of Illinois, have invented certain new and useful Improvements in Looper-Supports, of which the following is a description, reference being had to the accompanying drawing and to the letters and figures of reference marked thereon.

My invention relates to an improvement in sewing machines, the object being especially to provide a machine of the chain stitch type, which is capable of greater range and nicety of adjustment of the loopers than those heretofore used.

It has heretofore been proposed to provide a looper rocker with a plurality of sockets for the reception of several loopers, and also to provide the looper-supporting shaft with a plurality of rockers.

The present invention is more particularly an improvement on the latter invention, which is illustrated in the patent to Kramer, 25 885,624 of April 21st, 1908, whereby as above stated, greater variety and nicety of adjustment is accomplished, and whereby when adjusted, the looper rocker is positively held from lateral movement.

An object of the invention is to provide means for positively holding the pivot stud for the looper carrier from lateral movement on the looper support, which means is so constructed as to permit an adjustment 35 which is a fractional part only of the diameter of the supporting stud.

The invention is illustrated in the accompanying drawings, in which—

Figure 1 is a front elevation of a portion 40 of a sewing machine embodying my invention; Fig. 2 is a perspective view of a looper support embodying my invention; Fig. 3 is a rear side view; Fig. 4 is a rear side view, showing one of the pivot stud plates reversed; Fig. 5 is a section on the line 5—5 of Fig. 4; and Fig. 6 is a perspective view, showing the parts all detached.

In these drawings, 1 represents the base plate of a union special machine of a well 50 known type.

In the present instance, the invention is shown as applied to a machine having a very wide presser foot 2, with two adjustable needles arranged at a considerable distance 55 apart, but, of course, it will be understood

that the number and arrangement of needles may be varied, in accordance with the style of work or width of seam required to be sewed, the loopers, of course, being changed in number and arrangement, as hereinafter 60 will be described.

3 represents the usual looper support, pivoted at the end 4 to a stationary part of the machine frame, and at the other end 5 attached to the rock shaft driven from the 65 main shaft 6, whereby the usual sidewise or needle-avoiding movement is given the loopers carried by said looper support.

This looper support, as herein shown, is provided with two longitudinal slots 7, and in these slots, near the inner face of the looper support, are set, mortised or otherwise inserted, so as to be rigidly held, plates 8 having openings 9 just large enough to receive the end of the pivot stud 10, which is passed through said plate, and held securely by the nut 11. This headed bolt or pivot stud 10 passes through the looper carrier or rocker 12 and cone 13, the looper carrier or rocker being pivoted in the usual 70 way and operated by the pitman 14. As shown in the drawings, these plates are set in a recess formed in the looper support and the walls of this recess form members integral with the support for preventing 75 lateral movement of the plate.

The looper carrier or rocker 12 is connected with the other looper carrier or rocker by the adjusting rod 15. The shanks of the loopers 16 are set in the openings in the 80 sockets. The openings 9 in the plates 8 are set eccentrically, that is, nearer one end than the other, and by this arrangement and by taking out the plates and reversing their 85 position, considerable range of adjustment for the looper carriers is afforded, and when the plates have been inserted in the slots and the nuts 11 screwed on the pivot studs, no accidental displacement is possible.

It will be seen that by providing a number of plates with pivot stud openings arranged in respectively different positions, the greatest possible range of adjustment may be effected, and to facilitate the work of adjustment, the removable plates will be 100 suitably marked to indicate the gage of the machine.

Having thus described my invention, what I claim as new and desire to secure by Letters Patent, is—

1. The combination of a looper support, a looper carrier, a stud mounted on said support on which said carrier is pivotally mounted, and means for positively holding said stud from lateral movement relative to said looper support including a reversible plate having means for engaging said stud, and means for engaging and holding said plate from endwise movement on said looper support.
2. The combination of a looper support, a looper carrier, a stud mounted on said support on which said carrier is pivotally mounted, said looper support being slotted to receive said stud, a plate having an aperture therein fitting said stud, and means whereby said plate is held from lateral movement relative to said support.
3. The combination of a looper support, a looper carrier, a stud on said support on which said carrier is pivotally mounted, said support being slotted to receive said stud, a plate having an aperture therein fitting said stud, and means for holding said plate from lateral movement relative to said support, said aperture in said plate being located nearer one end thereof than the other, whereby the reversing of said plate adjusts said stud for the looper carrier relative to said support.
4. The combination of a looper support, a looper carrier, a stud on said support on
- which said carrier is pivotally mounted, a plate having an opening therein surrounding said pivot stud, said support having integral members for preventing lateral movement of said plate.
5. The combination of a looper support, a looper carrier, a stud on said support on which said carrier is pivotally mounted, a plate having an opening therein surrounding said pivot stud, said support having integral members for preventing lateral movement of said plate, the opening in said plate being located at one side the center thereof, whereby the reversing of said plate adjusts the looper carrier stud relative to said support.
6. In a sewing machine, the combination with a needle bar carrying a plurality of spaced needles, a looper support, a series of looper carriers arranged respectively upon opposite sides of the needle bar, each looper carrier having a pivot stud for the carrier, and means whereby said pivot stud may be adjusted fractional parts of the diameter of the stud and positively held from lateral movement when adjusted.

In testimony whereof I affix my signature, in presence of two witnesses.

FRANCIS S. NORTH.
